US00D795249S

(12) **United States Design Patent** (10) **Patent No.:** **US D795,249 S**
(45) **Date of Patent:** **** Aug. 22, 2017**

(54) **ELECTRONIC DEVICE**

(71) Applicant: **Amazon Technologies, Inc.**, Seattle, WA (US)

(72) Inventors: **Timothy Eli Wall**, San Francisco, CA (US); **Marc Rene Walliser**, San Francisco, CA (US)

(73) Assignee: **Amazon Technologies, Inc.**, Seattle, WA (US)

(**) Term: **15 Years**

(21) Appl. No.: **29/560,832**

(22) Filed: **Apr. 11, 2016**

(51) LOC (10) Cl. **14-02**

(52) U.S. Cl.

USPC **D14/341**

(58) **Field of Classification Search**

USPC ..... D14/341-347, 137, 138 R, 138 AA, D14/138 AB, 138 C, 138 G, 496, 203.1, D14/203.3, 203.4, 203.7, 129, 130, 147, D14/218, 247, 248, 250, 385, 388, 389, D14/315-318, 420, 426, 439; D21/329, D21/330; D10/50, 65, 104.1; D6/308-310

(57) **CLAIM**

The ornamental design for an electronic device, as shown and described.

DESCRIPTION

FIG. 1 is a front perspective view of an electronic device showing the new design;

FIG. 2 is a back perspective view of thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines shown in the drawings illustrate portions of the electronic device that form no part of the claimed design.

1 Claim, 8 Drawing Sheets
